Inventor:

Charles A. Stickney,

By Spear, Middleton, Donaldson & Spear
4/17/95.

UNITED STATES PATENT OFFICE.

CHARLES A. STICKNEY, OF CHATTANOOGA, TENNESSEE, ASSIGNOR, BY DIRECT AND MESNE ASSIGNMENTS, TO ADDRESSOGRAPH COMPANY, OF CHICAGO, ILLINOIS, A CORPORATION OF ILLINOIS.

PUNCH AND DIE FOR EMBOSSED CHARACTERS AND RAISING BOSSSES THEREFOR PREVIOUS TO THE EMBOSSED ACTIONS.

1,301,383.

Specification of Letters Patent. Patented Apr. 22, 1919.

Application filed April 8, 1918, Serial No. 227,289. Renewed March 6, 1919. Serial No. 281,076.

To all whom it may concern:

Be it known that I, CHARLES A. STICKNEY, a citizen of the United States, and resident of Chattanooga, Tennessee, have invented certain new and useful Improvements in Punches and Dies for Embossing Characters and Raising Bosses Therefor Previous to the Embossing Actions, of which the following is a specification.

10 The invention relates to dies for embossing printing plates as used in addressing machines, and the like and particularly to that class of dies which displace the metal of the plate to one side of its normal plane and forms the embossing on this raised or displaced portion of the metal.

Hitherto dies have been used which raise or displace the base of the letter, and by the same punching act the character is embossed 20 on this raised or displaced portion.

In carrying out my invention I provide a die and punch which will displace or raise the metal of the plate in advance of the point or location at which the character is 25 formed on the previously formed raised portion, so that at each action of the die and punch a character will be formed on a raised portion of the plate and at the same time the metal of the plate will be displaced in 30 advance of the position where the character is formed, so that at the next action of the die and punch a character will be embossed on this last mentioned raised portion, while at the next position in advance the metal 35 of the plate will be displaced or raised ready to receive the next embossing and so on, the displacing of the metal of the plate taking place simultaneously with the formation of the characters, but always in advance 40 of the position where the embossing of the character is done.

The invention is shown in the accompanying drawings in which,

Figure 1 is a sectional view showing a 45 pair of dies to preliminarily form a cone or displaced portion of the metal for receiving the formation of the character thereon by the pair of dies shown in Fig. 2.

Fig. 2 is a vertical sectional view through 50 a die and punch, the position of the parts being that just previous to the formation of

the character on the cone already formed and the formation of a new cone portion.

Fig. 3 is a view similar to Fig. 2 showing the next step in the operation subsequent to 65 that of Fig. 2.

Fig. 4 is a face view of the die.

Fig. 5 is a sectional view on the line 5—5 of Fig. 3.

Fig. 6 is a perspective view of the die, and 60 Fig. 7 is a perspective view of the punch.

In starting to emboss a plate dies like those shown in Fig. 1 are first brought into action upon the plate to form a cone 8 by displacing the metal of the plate to one side 65 of its main body portion. After this is done the plate is subjected to the action of a punch and die of the form illustrated in Figs. 2 to 7, the die *a* having a plain face 9 with the recess or groove 10 therein for forming the character and having off to one side of this plain face ribs or projections 11, extending above the same, and with a recess 12 between them. The punch *b* has a raised portion 13 thereon with a rib 14 correspond- 70 ing to the recess 10 in the die and it has also a raised portion 15 to enter between the projections 11. In Fig. 2 the die and punch are about to perform their functions in connection with the plate and Fig. 3 shows the 75 condition of the plate after the punch has been brought down to the limit of its stroke from which it will be seen that the character is raised at *x* between the rib 14 and groove or recess 10 of the punch and die faces and 80 the portion 15 of the punch depresses or displaces the metal of the plate in advance of the position where the letter is embossed, this displacing action being effected by the projecting portion 15 of the punch operat- 85 ing between the ribs or projections 11 of the die. At the next die action the plate is shifted so that a character is embossed on the displaced cone at the right of Fig. 3 and 90 a new cone portion will be formed, and this action is repeated until the line of characters is completed.

It will be seen that the first stroke of the punch and die raises a cone for the next 100 succeeding operation to emboss the letter on and each distortion of the metal in raising the cone is a step in advance of the emboss-

ing action. As a result of this when the punch and die form the character this is done on a cone already raised, and there will be no deflection or tipping of the raised or 5 cone portion of the plate.

My improved punch and die allows much closer line spacing than dies used heretofore, because there is no part of the die proper located above or below the embossing 10 portion or face which projects above said face, and the character forming groove and rib may extend close to the top and bottom of the punch and die faces.

The operation may be completed at the 15 end of a line by blanking down the last cone portion which has no character embossed thereon.

What I claim is:

1. A punch and die for embossing metal 20 plates, said die having a face with a character forming recess and a portion to one side of said face which in coöperation with the punch will displace the metal of the plate to form a raised base for the embossing of the next character thereon by said 25

character forming portion, said punch having portions complementary to the character forming recess and the portion to one side of the same, substantially as described.

2. A punch and die for embossing metal 20 plates, said die having a face with a character forming recess and a laterally disposed recess which in coöperation with the punch will displace the metal of the plate to form a raised base for the embossing of the next 35 character thereon by said character forming portion, said laterally disposed recess having marginal ribs extending from one side of the die and projecting above the plane of the character forming face and in line 40 with the upper and lower portions of said face, said ribs being of a length substantially equal to the width of the character forming face, said punch having portions complementary to the character forming recess and the laterally disposed recess, substantially as described.

In testimony whereof I affix my signature.

CHARLES A. STICKNEY.
